US00D359059S

United States Patent [19]**Omi**[11] **Patent Number:** **Des. 359,059**[45] **Date of Patent:** **** Jun. 6, 1995**[54] **PROJECTION MICROSCOPE**4,621,913 11/1986 Yamada et al. .... 359/369 X
5,307,098 4/1994 Okita ..... 353/76 X[75] Inventor: **Shoichi Omi**, Tokyo, Japan*Primary Examiner*—A. Hugo Word[73] Assignee: **Lunax Company Limited**, Ibaraki,
Japan*Assistant Examiner*—Catherine R. Oliver*Attorney, Agent, or Firm*—Popham, Haik, Schnobrich &
Kaufman, Ltd.[**] Term: **14 Years**[57] **CLAIM**[21] Appl. No.: **15,671**The ornamental design for a projection microscope, as
shown and described.[22] Filed: **Nov. 24, 1993****DESCRIPTION**[30] **Foreign Application Priority Data**

May 24, 1993 [JP] Japan 5-15017

FIG. 1 is a perspective view of a projection microscope
showing my new design, taken from a front, right and
upper position thereof;[52] U.S. Cl. **D16/131; D16/225**

FIG. 2 is a front view of the projection microscope;

[58] **Field of Search** D16/131, 130, 100, 221;

FIG. 3 is a rear view of the projection microscope;

359/368, 369; 353/39, 71, 74, 75, 76, 77, 78, 98,
99, 38

FIG. 4 is a plan view of the projection microscope;

[56] **References Cited**

FIG. 5 is a bottom view of the projection microscope;

U.S. PATENT DOCUMENTS

FIG. 6 is a left side view of the projection microscope;

D. 204,964 5/1966 Wally D16/225
3,205,770 9/1965 Koch et al. 353/39
3,572,884 3/1971 Chirayath 359/369
4,206,966 6/1980 Tyson 359/369

FIG. 7 is a right side view of the projection microscope;

FIG. 8 is a perspective view of the projection micro-
scope in which a screen is halfway drawn out; and,FIG. 9 is a perspective view of the projection micro-
scope in which a screen is completely withdrawn.FIG. 1
